UNITED STATES PATENT OFFICE.

WILLIAM HENDRY, OF TACOMA, WASHINGTON.

DESIGN FOR AN AUTOMOBILE TAIL OR SIGNAL LIGHT.

57,648.

Specification for Design.

Patented Apr. 26, 1921.

Application filed May 29, 1920. Serial No. 385,372. Term of patent 14 years.

To all whom it may concern:

Be it known that I, WILLIAM HENDRY, a subject of the King of England, and resident of the city of Tacoma, county of Pierce, and State of Washington, have invented a new, original, and ornamental Design for an Automobile Tail or Signal Light, of which the following is a specification, reference being had to the accompanying drawings, forming part thereof.

Figure 1 is a front view of an automobile tail and signal light, formed according to the present design.

Fig. 2 is a side view, partly in section, of the same.

Fig. 3 is an end view of the housing.

I claim:

The ornamental design for an automobile tail or signal light, as shown.

WILLIAM HENDRY.
